UNITED STATES PATENT OFFICE.

JOHN A. LUTHER, OF SCHENECTADY, NEW YORK.

SPARK-PLUG.

1,380,399.

Specification of Letters Patent.

Patented June 7, 1921.

Application filed July 25, 1919. Serial No. 313,342.

To all whom it may concern:

Be it known that I, JOHN A. LUTHER, a citizen of the United States, residing at Schenectady, in the county of Schenectady, State of New York, have invented certain new and useful Improvements in Spark-Plugs, of which the following is a specification.

The present invention relates to spark plugs for internal combustion engines and has for its object to improve their construction. My improvements are directed principally to the means for supporting the porcelain or other insulator for the central electrode whereby the breakage thereof both in manufacture and use will be decreased to a minimum, and also to the means for insuring air tight seals between the porcelain or other insulator and its metal support or shell and between the central electrode and the surrounding insulator. Additional features of my invention are the means for protecting the insulator from injury when the plug is being screwed into or removed from the engine cylinder, and the arrangement for conveying heat away from the interior parts of the plug.

For a consideration of what I believe to be novel and my invention, attention is directed to the accompanying description and claims appended thereto.

In the drawing, Figure 1 is a view in elevation of a spark plug with a portion of the casing cut away in quarter section and Fig. 2 is an axial section of the same.

5 indicates the metal shell or casing of the plug which is threaded at one end to enable it to be screwed into the engine cylinder or other support. It is provided with the usual flange or shoulder 6 between which and the cylinder or support is located a suitable packing or gasket, not shown. The opposite end of the shell is provided with a hexagon head 7 to receive a suitable wrench. Inside 45 the shell is an annular shoulder 8 upon which the porcelain or other insulator 9 is seated. The head of the shell is also internally threaded to receive the tubular member 10 which has several functions. First it acts as an abutment for the shock absorbing coiled compression spring 11 which holds the insulator on its seat; second it acts as a guard to prevent injury to the insulator; third it acts as a guide for the outer 55 portion of the insulator; and fourth it

forms a part of the ventilating means. The member is screw threaded on its inner end for a suitable distance and adjacent the threads is a peripheral shoulder 12 which, when the shell and member are united, engages the shell and definitely positions the parts, and hence definitely limits the tension on the spring to a predetermined value. It is to be particularly noted that the inner end 13 of the member does not contact with the insulator in any way and therefore cannot cause any cracking or undue strains thereon when screwed into place, no matter how careless the assembler may be or how much pressure is employed in securing the parts together. The shoulder has two flat surfaces to receive a wrench, one of which is indicated at 14.

The outer end of the member is provided with an internal shoulder 15 which acts as an abutment for the outer end of the shock absorbing coiled compression spring 11. The spring is preferably made of flat stock since it permits the desired spring tension to be obtained without making the diameter unduly large. It is important not only from a manufacturing point of view to make the diameter as small as possible but also to facilitate mounting the plug in the engine. The insulator, it will be noted, is cylindrical with a shoulder or an enlarged portion 16 which rests on the internal shoulder on the shell, there being a copper or equivalent gasket 17 to form a seal. The opposite side of the enlarged portion is also provided with a copper or equivalent gasket 18 upon which the inner end of the spring rests. The spring when mounted in place should be under sufficient compression to hold the insulator on its seat even when it is subjected to the high pressure of the burning charge of combustible in the cylinder. The spring will, however, compensate for changes due to different rates of expansion of the parts and also absorb shocks to which the plug is subjected while in operation.

It is to be particularly noted that any shocks to which the insulator is subjected due to the firing of the charge in the cylinder are absorbed by the spring instead of being directly transmitted to the casing, and hence breakage of the insulator is prevented.

In practice the springs are cut to the desired length and their ends properly finished so as to seat squarely on the insulator at

one end and engage the internal shoulder on the member at the other. To assemble the parts the insulator is slipped into place in the shell, then the spring, after which the member is screwed into place. No damage can occur to the insulator because there are no non-yielding parts which grip it as in the ordinary construction. The assembler merely screws the member to its seat and the 10 spring does the rest, the tension of the latter having been previously determined. This means that nothing is left to the individual skill of the assembler and the bugbear of loose or cracked insulators is overcome.

15 The central electrode 19 is provided with a collar 20 which is seated on a shoulder on the insulator, and between the collar and shoulder is a washer or gasket to maintain an air tight seal. The inner end of the 20 electrode projects beyond the inner part of the shell and standing adjacent to it but separated by a suitable air gap is a second electrode 21 carried by the shell and grounded of course, to the engine. The outer end of 25 the center electrode 19 is screw-threaded and passes through a secondary insulator 22, the latter being guided or held central by the bore of the internal shoulder on the member. Between the main and secondary insulators 30 there is or may be a suitable gasket 23 which serves as an additional means to prevent the escape of gas from the cylinder around the central electrode. On the electrode and outside the insulator 22 is a clamping nut 24 which may with advantage be made round 35 and adjusted by a pair of pliers. Under the nut is a lock washer 25, and below that a copper or other disk. Over the nut 24 is a second nut 25^a which acts as a lock-nut for the 40 first and also as a seat for the ignition lead which is connected to the plug and to a source of current. 26 indicates the nut for holding the lead in place. By arranging the nut 24 as described there is no danger of a 45 careless person accidentally disturbing the clamping device 24 of the central electrode which would permit air to leak around it into the cylinder.

In order to keep the internal parts of the 50 plug from becoming unduly hot, the head of the shell is provided with ventilating openings 27 which are adjacent the enlarged part of the main insulator. Other ventilating openings 28 are provided in the tubular 55 member and through all of the openings air is permitted to freely circulate. In particular, the ventilating arrangement is useful in preventing the spring from being overheated and losing its temper.

60 In case the plug gets foul the central electrode can be removed from the under side for cleaning by removing the nuts 24, 25 and 26. The main insulator is not disturbed because it is held in position by the compression spring and the tubular member. By

this arrangement the chance of injuring the porcelain or main insulator is reduced to a minimum.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States is:—

1. In a spark plug, the combination of a shell adapted to be attached to a support 80 and provided with an internal shoulder, a stationary insulator mounted within the shell and having an enlarged portion which is seated on the shoulder, a shock absorbing compression spring which surrounds the insulator and forms the means for holding it on its seat against cylinder pressure, an abutment for the outer end of the spring, a stationary electrode which passes through the insulator and is adapted to be connected to 90 a source of current, and a second electrode co-operating with the first and permanently separated therefrom by an air gap.

2. In a spark plug, the combination of a shell which is screw-threaded externally for 95 attachment to a support and has an internal shoulder, an insulator which has an enlarged portion on the shoulder, a coiled compression spring which surrounds the insulator and holds it on its seat against cylinder pressures, a member which forms an abutment for the outer end of the spring and is attached to the shell, an electrode which passes through the insulator, and a second electrode supported by the shell.

3. In a spark plug, the combination of a shell which is screw-threaded externally at one end and internally at the other, and is provided with an internal shoulder, a stationary insulator which is seated on the shoulder and forming a gas-tight seal, a member which surrounds the insulator and is screw-seated on the shell at one end and has an internal flange at the other, a shock absorbing compression spring which holds the insulator on its seat against cylinder pressure and in turn is held under compression by the flange, and an electrode which passes through the insulator from end to end and is permanently separated from the 120 shell by an air gap.

4. In a spark plug, the combination of a shell which is screw-threaded externally at one end and internally at the other, and is provided with an internal shoulder, a stationary insulator which is seated on the shoulder, a member which surrounds the insulator and is screw-threaded at one end for attachment to the shell, carries a spring abutment, and has an external shoulder 130

which is seated on the outer end of the shell, a shock absorbing compression spring which rests on the insulator at one end to hold it on its seat against cylinder pressure and at the other end engages the abutment, the tension of the spring being determined by said shoulder, and a stationary electrode which passes through the insulator and is permanently separated from the shell by an air gap.

5. In a spark plug, the combination of a screw-threaded shell, having an internal shoulder, an insulator which engages the shoulder, a tubular member screw-threaded to the shell and inclosing the insulator, a coiled compression spring which holds the insulator on its seat against cylinder pressure and is retained under compression by the member, and ventilating passages formed in the shell and member through which air is free to flow over the spring.

6. In a spark plug, the combination of a screw-threaded shell having an internal shoulder, an insulator mounted on the shoulder, a member which incloses the insulator and is attached to the shell, a spring within the member which holds the insulator on its seat, a secondary insulator supported by the first and guided by the member, and an electrode which passes through both insulators, is seated pressure tight in one and forms a means for uniting both.

7. In a spark plug, the combination of a screw-threaded shell having an internal shoulder, an insulator mounted on the shoulder, a member which incloses the insulator and is attached to the shell, a spring within the member which holds the insulator on its seat, a secondary insulator supported by the first and guided by the member, an electrode which passes through both insulators and is seated pressure tight, a nut on the electrode which clamps the two insulators together, and a second nut on the electrode which covers the first to prevent accidental displacement and forms a part of an electric terminal.

8. In a spark plug, the combination of a shell adapted to be attached to the engine and which is provided with an internal shoulder, an insulator having an enlarged portion which is seated on the shoulder, a member threaded to the shell which surrounds the insulator and is spaced there-

from at all points to permit the parts to 55 freely move relative to each other, a shoulder on the member which limits its inward movement, and a coiled compression spring located in the space between the insulator and the member which forms the sole means 60 for holding the insulator pressure tight on its seat, said spring absorbing shocks to which the insulator is subjected.

9. In a spark plug, the combination of a metal shell which is screw-threaded at 65 opposite ends and has an internal shoulder, a stationary insulator which is provided with an enlargement between its ends, the under surface of which is supported by the shoulder, a tubular member which has 70 screw threads that engage those at the outer end of the shell and also a spring abutment, means for limiting the amount that the member can be screwed downward with respect to the shell, a shock absorbing spring 75 which surrounds the insulator, one end of said spring pressing on the enlargement on the insulator, the other end engaging the abutment, an electrode which passes through the insulator, and a second electrode which 80 is supported by the shell and separated from the first by a permanent air gap.

10. In a spark plug, the combination of a metal shell which is screw-threaded at opposite ends and has an internal shoulder, 85 a gasket which rests on the shoulder, a stationary porcelain insulator which has a shoulder that is seated on the gasket, a hollow member which surrounds the insulator, has screw threads which engage those 90 on the outer end of the shell and also an internal spring abutment, a shock absorbing spring which surrounds the outer portion 95 of the insulator and presses on its shoulder at one end and engages said abutment at the other, means for limiting the amount 100 that the member can be screwed downward with respect to the shell, thereby definitely limiting the pressure that the spring can exert on the insulator, and an electrode which extends centrally through the insulator and is permanently separated from the inner end of the shell by a permanent air gap.

In witness whereof, I have hereunto set 105 my hand this 23rd day of July, 1919.

JOHN A. LUTHER
